UNITED STATES PATENT OFFICE.

ERNEST L. COLBY, OF PUEBLO, COLORADO.

SPARK-PLUG.

1,374,281.

Specification of Letters Patent. Patented Apr. 12, 1921.

Application filed March 16, 1920. Serial No. 368,285.

To all whom it may concern:

Be it known that I, ERNEST L. COLBY, a citizen of the United States, residing at Pueblo, county of Pueblo, State of Colorado, 5 have invented new and useful Improvements in Spark-Plugs, of which the following is a specification.

This invention pertains to spark plugs, and particularly to the electrode and insulating structure as embodied in such plugs.

An object of the invention is to provide a spark plug embodying means which will prevent the formation of a hydrocarbon fluid film to short circuit across the insulating material, and also to prevent carbon 10 from coating the same which will result in short circuiting the plug.

A further object resides in arranging obliquely disposed baffles at the inner end of 20 the orifice of the shell of the spark plug as guards against the entrance of hydrocarbon fluid or carbon laden gases.

Another object resides in so constructing the central electrode that it clears the baffles 25 and is at the same time sufficiently spaced from the shell structure to insure against short circuiting and consequent sparking except across the spark gap.

Yet another object is to provide a spark 30 plug embodying the features above stated which can be efficiently and cheaply manufactured, and which presents the parts in such relation that there is little possibility of the spark plug becoming fouled, short 35 circuited through carbon deposits, or otherwise rendered unfit for the purpose intended or inoperative in use.

With these and other objects in view which will be apparent from the drawings, 40 specification and claims, this invention includes certain novel features of construction and combination of parts which will now be set forth.

In the drawings:

45 Figure 1 is a view in elevation of a spark plug constructed after the manner of my invention.

Fig. 2 is a view in vertical section through the plug.

50 Fig. 3 is a view in elevation of the sparking end of the plug.

Fig. 4 is a transverse sectional view on line 4—4 of Fig. 2.

55 Fig. 5 is a view similar to Fig. 4 taken on line 5—5.

Fig. 6 is an enlarged perspective view of

the inner end of the central insulator to better show the formation of the central electrode.

Fig. 7 is a fragmentary sectional view 60 showing a slightly modified construction of plug and the use of a greater number of baffles.

Fig. 8 is a view similar to Fig. 7 showing an adaptation suitable for plugs having a 65 short shell.

Fig. 9 is a view in elevation of the sparking end of the plug illustrated in Fig. 8.

Fig. 10 is a perspective view of the sleeve by which the baffles are mounted in the last 70 mentioned adaptation.

In the main embodiment I have shown a shell 1 of the type having an extension 2. This shell is bored to provide a central chamber 3 at its inner end which is received 75 in the engine cylinder, and at its outer end is internally screw threaded to take packing gland 4.

A central insulator 5, of porcelain or other suitable material, is fitted within the 80 shell to rest upon a shoulder 6 and is held in place by packing gland 4, a suitable packing washer being preferably fitted between these members to establish a fluid tight connection. The central electrode 7, carried by 85 insulator member 5 is threaded at its outer end or is otherwise formed to provide a suitable binding post or terminal connection, the thumb nut 8 being here shown simply as a means of establishing terminal 90 connection.

The extension 2 of shell 1 has the slightly spaced slits 9 and 10 formed on opposite sides and extending slightly past an axial center. These slits may be formed as saw 95 slots or may be otherwise cut, and are preferably extended at oblique angles from their point of starting on the outer wall to their inner ends, the angle of inclination being toward the open end of chamber 3. Substantially semi-circular baffle members 11 and 12 are secured in these slits and are thus presented as obliquely set baffles guarding the open end of chamber 3, the extension of the inner edge of each baffle member past a medial line positively precluding the direct flow of fluid from the engine cylinder into the body of the chamber to precipitate carbon or other deposits around and upon the central electrode. 100

By this arrangement of the baffles the opening from the body of the chamber 3 to

the outer end is made circuitous, and to suit this condition central electrode 7 is bent angularly to have a zigzag form, as best shown in Fig. 6, in that part extending beyond 5 the central insulator. By this formation of the central electrode the baffles 11 and 12 are cleared when the parts of the plug are assembled, and a sparking terminal 13 is presented at the open end of chamber 10 3, this sparking terminal being near the center.

The shell 1 and its extension 2 are the ground structure of the plug, and care is of course to be exercised in the formation of 15 the central electrode 7 so that it clears this ground structure at all points from central insulator 5 to its sparking terminal 13 that all danger of short circuiting is precluded. This sparking terminal 13 might be extended 20 sufficiently to provide a spark gap directly between the terminal and the shell structure, however it is preferable that a ground electrode terminal 14 carried by the shell structure be formed to extend in proximity 25 to sparking terminal 13 to thus more nearly center the spark gap with respect to the open end of chamber 3.

The parts are assembled after the manner shown in Figs. 1 and 2, and the plug is inserted 30 in the usual manner in the opening of the cylinder, the chamber 3 then opening into the explosion chamber. The plug is connected in the usual ignition circuit and when current is passed through this circuit 35 the spark will jump the gap between terminals 13 and 14. The arrangement of the baffles set on an oblique angle out from opposite points in the shell presents a guard against the inrush of hydrocarbon or other 40 fluid from the cylinder and thus with my improved spark plug there is little likelihood of the formation of a fluid film or of a carbon coating to short circuit across the insulating material. The baffle members 11 45 and 12 are made up of several sheets of mica combined to give the requisite strength, or are made up of other suitable insulating material, and thus short circuiting from the central electrode to these baffles is not possible.

With the modified construction as shown in Fig. 7, the shell 15 has a somewhat longer extension 16, than is shown in the main embodiment, and with this form the four 55 baffle members 17, 18, 19, and 20 are employed. These baffle members are arranged to extend alternately from opposite points within the chamber of extension 16, and due to the staggered arrangement a double 60 guard is provided in the open end of the chamber. The central electrode 21 is bent to a zigzag form to clear the several baffles and a ground sparking terminal 22 carried by extension 16 is disposed adjacent the terminal 23 of the central electrode. It is pref-

erable that at least two baffle members be employed as where two are used and each extends past a medial line the direct passage into the chamber is closed. It will be appreciated that three baffle members might be used or that a greater number than four may be employed.

In the adaptation in Figs. 8, 9, and 10, the shell 24 of the spark plug is relatively short and has comparatively no extension beyond 75 the threaded portion, it thus being inexpedient to cut into or slit the shell to receive the baffles, and to overcome this difficulty I provide an inner bushing 25 by which baffles 26 and 27 are mounted. The 80 shell 24 is reamed or otherwise enlarged in the central chamber as at 28, and the bushing 25 is fitted therein. This bushing may be secured in place in any manner, and can be fitted removably in place if desired. The 85 central electrode 29 is substantially of the same form as electrode 7, shown in Figs. 2 and 6, however the central insulator will be shorter in that portion extending within the chamber of the shell. Ground electrode terminal 30 is formed in much the same manner as terminal 14.

While the baffle members might be secured in place in any desired manner, I have found it expedient to fix these members and clamp the same in place, substantially as shown in Fig. 10, by forming a line of center punch holes 31 in the metal adjacent each baffle member to expand the member to grip and clamp the same against 95 movement. This same method of securing may be employed in fixing the baffle members in the extension of the sleeve, or some other method accomplishing the desired result can be carried out.

While in the foregoing, I have shown and described only certain specific embodiments and have referred to possible modifications, it will be appreciated that in practice other changes in the construction and arrangement of the parts can be resorted to, in view of which I do not wish to be limited to the exact disclosure but to such embodiments of my invention falling within the scope of the appended claims.

I claim:

1. A spark plug including with a shell having a chamber at its inner end, a plurality of obliquely arranged baffles in staggered relation within said chamber with 120 their inner edges extending past the axial center of said chamber and angularly toward the open end thereof.

2. A spark plug including with a shell having a chamber at its inner end, a plurality of obliquely arranged baffles in staggered relation within said chamber with 125 their inner edges extending past the axial center of said chamber and angularly toward the open end thereof, and a central 130

electrode member bent to zigzag form to clear said baffles and to extend from the end of said chamber.

3. A spark plug including with a shell 5 having a chamber at its inner end, a plurality of obliquely arranged substantially semi-circular baffles of insulating material in staggered relation within said chamber with their inner edges extending past the 10 axial center of said chamber and angularly toward the open end thereof.

4. A spark plug including with a shell having a chamber at its inner end, a plurality of obliquely arranged substantially 15 semi-circular baffles of insulating material in staggered relation within said chamber with their inner edges extending past the axial center of said chamber and angularly toward the open end thereof, a central electrode 20 bent angularly to a zigzag form to clear said baffles and project a terminal from said chamber, and a ground electrode terminal carried by said shell extended adjacent said projecting terminal.

5. A spark plug including with a shell 25 having an orifice at its inner end, a sleeve received in said orifice, and a plurality of oppositely disposed substantially semi-circular baffles of insulating material mounted within said sleeve with their inner edges extending past the axial center of said orifice and obliquely at an angle toward the open 30 end thereof.

6. A spark plug including with a shell having an orifice at its inner end and having 35 slits formed through opposite sides thereof in staggered relation extending past the axial center of said orifice and obliquely disposed angularly toward the open end thereof, and baffle members fitted within said 40 slits and held in place by a line of center punch indentations formed on the outer side of the shell adjacent the metal thereof against said baffle members.

In testimony whereof, I affix my signature.

ERNEST L. COLBY.
